UNITED STATES PATENT OFFICE.

ELZIE M. WALTERS, OF UNIONTOWN, PENNSYLVANIA.

COMBINATION-WRENCH.

No. 860,949.

Specification of Letters Patent.

Patented July 23, 1907.

Application filed April 6, 1907. Serial No. 366,765.

To all whom it may concern:

Be it known that I, ELZIE M. WALTERS, a citizen of the United States of America, residing at Uniontown, in the county of Fayette and State of Pennsylvania, have invented certain new and useful Improvements 5 in Combination-Wrenches, of which the following is a specification, reference being had therein to the accompanying drawing.

This invention relates to wrenches, and the invention has for its primary object to provide a novel 10 wrench having gripping jaws or surfaces that can be renewed when worn.

Another object of this invention is to provide a wrench having detachable gripping jaws or blocks, 15 positive and reliable means being employed for holding the jaws or blocks in engagement with the wrench.

A further object of this invention is to provide a wrench having a novel attachment particularly designed for gripping polished surfaces, whereby when 20 an object is being rotated, the wrench will not injure the polished surface thereof.

A still further object of this invention is to provide a simple and inexpensive wrench that can be easily and quickly adjusted for gripping curved or flat surfaces, the wrench being designed to perform the work 25 ordinarily accomplished by a plurality of wrenches of various types.

With the above and other objects in view, which will more readily appear as the invention is better 30 understood, the same consists in the novel construction, combination and arrangement of parts to be hereinafter more fully described and then specifically pointed out in the appended claims.

Referring to the drawing forming part of this specification, like numerals of reference designate corresponding parts throughout the several views, in which:—

Figure 1 is a side elevation of my improved wrench, the handle or holder thereof being broken away, Fig. 40 2 is a similar view illustrating the gripping blocks or jaws removed therefrom, Fig. 3 is a front elevation, the clamps for the gripping blocks being removed, Fig. 4 is a front elevation of one of the gripping block clamps, Fig. 5 is a front elevation of another clamp, Fig. 6 is a perspective view of one of the gripping 45 blocks for curved surfaces, Fig. 7 is a perspective view of a gripping block having a smooth outer face for contacting flat surfaces, Fig. 8 is a perspective view of an attachment used in connection with my improved wrench for gripping cylindrical surfaces.

To put my invention into practice, I construct my improved wrench of a shank 1 having threads 2 upon two diametrically opposed edges, the remaining edges of the shank being smooth and flat. The shank 1 is 55 provided with a fixed jaw 3, said jaw being formed

with teeth 4 and cut away as at 5, to accommodate a clamp 6, said clamp being provided with a dowel pin 7 for centering the same upon the end of the jaw 3, and with a set screw 8 for holding the clamp upon the jaw. The jaw 3 and the clamp 6 are provided with 60 dowel pins 9, for centering a detachable gripping block 10 upon the jaw 3, said gripping block upon oppositely disposed faces being provided with teeth 11 and 12, the teeth 11 meshing with the teeth 4 of the jaw 3, and providing a positive connection between 65 the block 10 and the jaw 3, whereby stress and strain exerted upon the block when gripping a surface will be relieved from the clamp 6.

Upon the shank 1 is mounted a movable housing 14, 70 said housing being provided with a knurled nut 15, through which the shank 1 passes, said nut being provided with interiorly arranged threads to engage the threads 2 of the shank 1. The nut 15 is provided with radially disposed openings 15^a, whereby a suitable instrument can be inserted in the nut for further rotating 75 the same after it has been tightened. One edge of the housing 14 is bifurcated to provide pierced lugs 16 and guide lugs 17, said guide lugs being adapted to engage ears 17^a carried by the handle or lever 20. Between said lugs is pivotally mounted by a pin 18, a movable 80 jaw 19; said jaw being provided with a handle or lever 20. The jaw is provided with teeth 21 and with a detachable T-shaped clamp 22, said clamp being secured to the jaw by a set screw 23. The clamp 22 and the jaw 19 carry dowel pins 24, said dowel pins centering a detachable block 25 upon the jaw 19, said block having a flat smooth outer face 26, intended for use in gripping flat surfaces.

The housing 14 is provided with a depending arm 27^a and interposed between said arm and the handle or lever 20 is a coiled spring 27, said spring seating in the handle or lever 20, as at 28. The spring is employed for normally holding the shank 1 parallel to the handle or lever 20.

In Fig. 8 of the drawing, I have illustrated an attachment for my improved wrench, said attachment comprising a semi-cylindrical sleeve 29 with a smooth concaved outer face, and having teeth 30 adapted to engage the teeth 21 of the jaw 19 or the teeth 4 of the jaw 3. This attachment is particularly designed for gripping polished surfaces such as brass or nickel plated pipes or tubes.

When it is desired to use my improved wrench for gripping flat surfaces, two of the blocks 25 will be employed, and for round surfaces two of the blocks 10 will 105 be employed, one set of blocks providing gripping teeth while the other set of blocks provides flat surfaces for engaging a nut or similar object.

The clamps 6 and 22 permit of the gripping blocks 110 being easily and quickly changed, whereby the wrench

can be used for numerous purposes, thus dispensing with the plurality of wrenches heretofore used by mechanics or similar artisans.

I do not care to confine myself to the size, proportion or minor details of construction, as such changes as are permissible by the appended claims, may be resorted to without departing from the spirit and scope of the invention.

What I claim and desire to secure by Letters Patent, 10 is:—

A wrench of the type described consisting of a threaded shank, a toothed jaw carried thereby, a toothed block adapted to engage the teeth of said jaw, a clamp, and 15 dowel pins carried by said jaw and said clamp for holding said block upon said jaw, said clamp secured upon said jaw by a dowel pin and set screw, a movable housing carried

by said shank, an adjusting nut arranged in said housing and engaging said shank, said nut being provided with radial openings, a movable jaw pivotally connected to said housing and having teeth, a toothed block adapted to engage the teeth of said jaw, a clamp for holding said block in engagement with said jaw, said jaw and clamp having each a projecting dowel pin, said clamp secured upon said jaw by a suitable set screw, a handle or lever carried by said jaw, and a coil spring seated in said handle or lever and contacting with a depending arm, carried by said housing, both said spring and arm being interposed between said handle or lever and said shank for normally holding said shank parallel to said handle or lever. 20 25

In testimony whereof I affix my signature in the presence of two witnesses.

ELZIE M. WALTERS.
